US00D835589S

(12) **United States Design Patent** (10) **Patent No.:** **US D835,589 S**
(45) **Date of Patent:** **** Dec. 11, 2018**

(54) **CONTROLLER FOR CONTROLLING CHARGING CURRENT**

(71) Applicant: **Jiangyin SINBON Electronics Co., Ltd.**, Jiangsu (CN)

(72) Inventors: **Xue-Feng Zhang**, Jiangsu (CN); **Jian Zhou**, Jiangsu (CN)

(73) Assignee: **Jiangyin SINBON Electronics Co., Ltd.**, Jiangsu (CN)

(**) Term: **15 Years**

(21) Appl. No.: **29/626,095**

(22) Filed: **Nov. 15, 2017**

(51) LOC (11) Cl. **13-03**

(52) U.S. Cl.

USPC **D13/171**

(58) **Field of Classification Search**

USPC D13/107, 108, 118, 119, 162, 168, 199; D14/218, 333, 358, 354

CPC B60L 11/1816; B60L 11/1818; B60L 11/1851

See application file for complete search history.

(57) **CLAIM**

The ornamental design for a controller for controlling charging current, as shown and described.

DESCRIPTION

FIG. 1 is a perspective view of a controller for controlling charging current, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an operational perspective view showing an embodiment of the claimed design; wherein the broken lines are shown for illustrative purposes only and form no part of the claimed design.
